Attn:

UNITED STATES PATENT OFFICE.

ORLAND F. BAUGHMAN, OF LAKEWOOD, OHIO, ASSIGNOR TO THE BANKERS SAVINGS AND CREDIT SYSTEM COMPANY, OF CLEVELAND, OHIO, A CORPORATION OF OHIO.

DESIGN FOR A COIN BANK.

Application filed September 4, 1924. Serial No. 10,676. Term of patent 14 years.

To all whom it may concern:

Be it known that I, ORLAND F. BAUGHMAN, a citizen of the United States, residing at Lakewood, in the county of Cuyahoga and State of Ohio, have invented a new, original, and ornamental Design for a Coin Bank, of which the following is a specification, reference being had to the accompanying drawing, forming part hereof, wherein—

Fig. 1 is a front elevation and Fig. 2 is a plan view of a coin bank exhibiting my new design.

I claim:

The ornamental design for a coin bank, as shown.

ORLAND F. BAUGHMAN.
